RACKET

John M. Le Compte, North Attleboro, Mass.

Application February 5, 1941, Serial No. 377,465

5 Claims. (Cl. 273—73)

This invention relates to a racket for various game uses, provided with a handle and a head frame containing strings.

The racket which is on the market in the more expensive forms has its strings rather tight. The strings are usually of lamb gut and are of a hygroscopic nature such as to cause tremendous strains to be exerted on the head frame when these strings become wet. Under such tremendous strains warping frequently occurs; and in studying the warping of a racket, I have found that the top portion of the head frame first moves inwardly under such strain. In Patent No. 2,220,935, dated November 12, 1940, of which I am one of the joint inventors, there is provided a support for this top portion by a novel means which has proven satisfactory. I find, however, that in light rackets I may eliminate the strengthening strands which extend over the outside surface and truss the frame from the inside of the racket head.

Accordingly, one of the objects of this invention is to simplify the construction which I have heretofore provided, utilizing the strength given by added material attached to the frame at the points desired to be strengthened without the strand supporting this material as heretofore provided in the patent above referred to.

The invention also has similarly for its object to strengthen the head frame without unduly adding to the weight of the racket.

With these and other objects in view, the invention consists of certain novel features of construction, as will be more fully described, and particularly pointed out in the appended claims.

In the accompanying drawing:

Fig. 1 is a plan view of the head frame of the racket, with a portion of the handle shown as being broken away;

Fig. 2 is a view similar to Fig. 1, but showing a modified form of the invention;

Fig. 3 is a section on line 3—3 of Fig. 1;

Fig. 4 is a section on line 4—4 of Fig. 2;

Fig. 5 is a section of a fragmental portion of a modified head frame illustrating the strengthening portions of the head frame as formed out of the same stock as the frame;

Fig. 6 is a view similar to Fig. 5 except that the same is arranged as shown in Fig. 2;

Figs. 7 and 8 are modifications respectively of Figs. 1 and 2, illustrating a laminated strengthening of certain portions of the head frame; and

Fig. 9 is a section through one of the portions of increased dimension of the frame showing a

modified manner of holding the added member in place.

In carrying out this invention, I may either form the head frame from a single piece of material which has previously been cut to provide strengthening portions at desired locations, or I may add strengthening material by suitably securing it at the desired locations where the strengthening is desired. This may be done either by adding one suitably-shaped piece or by a laminated construction of the head frame.

With reference more particularly to the drawing, 10 designates the head frame of the racket which merges into the handle 11, and which frame has a top portion 12 and side portions 13. This head frame is provided with holes through which strings 14, usually of lamb gut, are placed in suitable spaced relation.

The strings that extend vertically in the mid portion of the racket and the strings that extend at right angles thereto, also in the mid portion of the racket, take the majority of strain in the use of the racket. From study it has been found that if warping occurs due to the tension 25 of these center strings, the first movement of the head which occurs is an inward bending at the top 12 of the head frame. Accordingly, in order to prevent such inward movement I have strengthened the frame by increasing its radial dimension at the location of the top mid portion. To strengthen this portion of the frame and prevent it from moving radially inwardly, I add material such as a member 15 secured firmly to the inner arcuate surface of the frame at this 35 location which, due to this larger area in cross section provided by the strengthening member 15, prevents inward bending at this location. While it is preferable that this member be inside of the curved portion of the head frame, in some 40 cases it may be located as at 16 in Fig. 2 outside, which also by the increased radial dimension of this portion of the frame strengthens the top portion so that it will not bend inwardly.

Similarly, it is found that at the mid portion 45 of the sides, the next weakest place, may also be strengthened by increasing the radial dimension of the frame at these locations, and I have added materials such as members 17 on the inside as in Fig. 1 or 18 on the outside as in Fig. 2, securely and firmly attached to this portion of the frame. With these strengthened portions at the locations 12 and 13 being of greater dimension than the head frame, I effectively prevent the moving inwardly of the frame at these locations and thus prevent warping of the racket without

detrimentally affecting its weight. Thus, by redistribution of the total weight of the head frame, I may, without increasing its weight, strengthen the same materially.

In Figs. 5 and 6, instead of adding portions such as 15, 16, 17 and 18, the head frame of the racket is formed of a single piece of material which is cut out so as to provide thickened portions 19 on the inside or 20 on the outside at the top and 21 on the inside or 22 at the outside along the sides, as shown in Figs. 5 and 6, the same theory being present in that this enlarged dimension provides the additional strength required to prevent inward bending at these locations at which bending will first occur, while strength at the other portions of the frame is unnecessary.

In Figs. 7 and 8, the head frame is laminated, there being a thick ply 23 and a thin ply 24 on the inside in Fig. 7 or a thin ply 25 on the outside as in Fig. 8; and between these plies I locate the strengthening members 15, 17 in Fig. 7, or 16, 18, as in Fig. 8, the plies assisting in holding the strengthening members in place and also providing a finish for the inside or outside of the racket.

These portions of greater dimension formed by the members 15, 16, 17, and 18 may be secured by glue which I have indicated in Figs. 1, 2, 3, 4, 7, and 8; or they may be secured by a screw 26 such as shown in Fig. 9.

I claim:

1. In a racket, a head frame carrying a plurality of strings, said frame being generally of a uniform radial dimension with a portion for a short extent of the length of the frame at the top thereof of a greater radial dimension than said other portions to resist bending at the said portions of greater dimension.
2. In a racket, a head frame carrying a plurality of strings, said frame being generally of a

uniform radial dimension with a portion at spaced intervals for a short extent of the length of the frame at the top thereof and at opposite sides of a greater radial dimension than said other portions to resist bending at the said portions of greater dimension.

3. In a racket, a head frame carrying a plurality of strings, said frame being generally of a uniform radial dimension with a portion for a short extent of the length of the frame at the top thereof of a greater radial dimension than said other portions to resist bending at the said portions of greater dimension, said portion of greater dimension being built up by reason of an added piece of material secured to the frame at the location of greater dimension.

4. In a racket, a head frame carrying a plurality of strings, said frame being generally of a uniform radial dimension with a portion at spaced intervals for a short extent of the length of the frame at the top thereof and at opposite sides of a greater radial dimension than said other portions to resist bending at the said portions of greater dimension, said portions of greater dimension being built up by reason of added pieces of material secured to the frame at the locations of greater dimension.

5. In a racket, a head frame carrying a plurality of strings, said frame being generally of a uniform radial dimension with a portion for a short extent of the length of the frame at the top thereof of a greater radial dimension than said other portions to resist bending at the said portions of greater dimension, said frame being formed of laminated material, said portion of greater dimension being built up by reason of an added piece of material secured to the frame at the location of greater dimension, and between the laminated plies.

JOHN M. LE COMPTÉ.
